UNITED STATES PATENT OFFICE.

ARTHUR HENRY LYMN, OF LONDON, ENGLAND, LEWIS ADAMS RILEY, 2d, OF NEW YORK, N. Y., AND NIELS EDWARD RAMBUSH, OF LONDON, ENGLAND.

GAS-PRODUCER.

1,380,993.

Specification of Letters Patent. Patented June 7, 1921.

Application filed October 31, 1916. Serial No. 128,746.

To all whom it may concern:
Be it known that ARTHUR HENRY LYMN, LEWIS ADAMS RILEY, 2d, NIELS EDWARD RAMBUSH, subject of the King of Great Britain, citizen of the United States of America, and subject of the King of Denmark, respectively, residing at 40 Westminster Palace Gardens, Victoria street, London, S. W., England, Vanderbilt Concourse Building, 10 52 Vanderbilt avenue, New York, U. S. A., and 40 Westminster Palace Gardens, Victoria street, London, S. W., England, have invented new and useful Improvements in and Relating to Gas-Producers, of which the 15 following is a specification.

Our invention relates to improvements in and relating to gas producers.
For obtaining the most economical results and the best gasifying effect the gaps formed 20 in the mass of the fuel due to caking must be filled up and clinkering of the ash must be prevented. This is effected by moderate agitation of the charge, and by admitting continuously new layers into the various 25 zones of reaction in the producer.

In order to attain an efficient agitation of the fuel, the producer may be provided with means which enable the whole or part of the contents of the producer to be moved in a 30 more or less horizontal as well as vertical direction; such movement of the producer contents causing agitation of the charge under treatment and a breaking up of parts which have caked or clinkered together.

The devices used for thus agitating the whole area and cross section of the charge 35 consisted of means for mechanically raising and lowering the whole or part of the revolving base in relation to the stationary 40 part.

In other devices the surface of the revolving grate comprises plates arranged side by side in the shape of a fan, the level of each plate gradually rising rearward from its 45 leading edge.

Other devices provided a grate or air distributor in itself concentric, but placed eccentrically to the axis of rotation or of a 50 grate or air distributor in itself eccentric, but placed concentric to the axis of rotation of the rotatable base which caused both a vertical and horizontal (lateral) displacement of the charge.

Other known devices generally consist of 55 a series of helical excrescences cut away to

form faces adapted to break up the clinker and convey the same toward the pan. In some cases the helical surfaces are so constructed that they gradually merge into a cylindrical contour. In other constructions 60 a conical grate is provided with spiral steps for pushing the ashes and incombustible matter toward its outer edge or periphery, curved ribs or vanes being provided at the outer termination of these steps for expelling the ashes. 65

In all these devices a great number of spaces is left between the projecting and cut-away portions of the surface which quickly fill up with hard setting clinker and 70 ashes so that the device is bound to act after a short time more or less as a cone thus failing not only to raise and lower the fuel but also to convey the ashes toward the shell of the producer. 75

Now the object of our invention is to obviate these disadvantages.

To effect the agitation of the lower part of the charge in a vertical as well as in a more or less horizontal direction a grate is 80 rigidly mounted upon a revolute ash bowl the whole or part of the under side of said grate adjacent to the producer contents is made of incomplete spiral, screw-propeller, whirl or similar configuration symmetrically 85 arranged around a center, the surfaces of which according to the invention have a very gradual rise terminated by abrupt shoulders of considerable depth. To obtain such gradual lifting surfaces and at the 90 same time to obtain a considerable drop, these surfaces and shoulders are necessarily few in number not exceeding four, and the shoulders are angularly widely separated.

In addition to such agitation in a vertical 95 direction as mentioned above, the grate or air distributor may be of such a shape that when same is revolved a further agitation of the charge takes place in a horizontal direction as well, preferably in such a direction as to cause a crushing and disintegrating of the lower portion of the charge 100 against the producer shell, and, simultaneously, a movement of the lowest portion of the charge in a direction toward the periphery of the ash bowl. 105

Such agitation of the producer charge in a horizontal direction may for example be effected by giving the grate the shape of vertical semi-cylinders eccentrically ar- 110

ranged relatively to each other and to the axis of rotation of the grate in such way that the cylindrical surfaces of said semi-cylinders at the ends remote from the axis 5 of rotation of the grate protrude laterally toward the producer shell.

In order that the details of construction and action of our invention may be more clearly understood, reference is made to the accompanying drawings which show by way of example apparatus suitable for carrying out our invention.

In the accompanying drawings:—

Figure 1 shows diagrammatically a sectional elevation of a gas producer with the agitating device;

Fig. 2 is a diagrammatic sectional plan on a larger scale showing the device for causing a crushing and disintegrating of the 20 charge against the lower part of the shell.

Fig. 3 is an elevation of the device used for simultaneously raising or lowering part of or the whole area of the charge as well as producing the movement of the lower 25 part of the charge in a horizontal direction;

Fig. 4 shows in sectional elevation a modification of said device actuated from the rotatable bowl, and also the grate and blast distributor; this latter section being taken 30 along the line $y-y$ of Fig. 2.

Referring to the drawings a indicates the revoluble ash bowl, b is the producer shell or casing, c the top of the producer and g is the grate or blast distributor.

35 In order to effect the simultaneous raising or lowering of the whole charge, at regular or irregular intervals the upper surface of the grate is constructed of one or more incomplete spirals or whirls; or the surface 40 may be formed in one or more raised faces shaped like screw propeller blades or wedges. It is however essential that the surfaces have a very gradual gradual rise terminated by abrupt shoulders of considerable 45 depth. This can only be done by providing a very limited number of projecting portions or shoulders not exceeding four.

The grate may also be so shaped that the rotation of the ash bowl causes the charge 50 of the producer to move in a more or less horizontal plane. The accompanying drawings show by way of example shapes suitable for this purpose. In Figs. 2 and 3 the sides of the grate have the shape of two 55 vertical half-cylinders laterally displaced along their dividing surfaces on the line $x-x$ (Fig. 2) which on revolving in the direction of the arrow shown in Fig. 2, displace said charge in the horizontal direction 60 toward the producer shell. In this way the crushing action on the ashes as mentioned above is effected. Fig. 4 shows the annular channels r' and the tangential holes r^2 for admitting blast to the charge. The blast is 65 admitted from below the grate at r^3 and

partly leaves peripherally around the device for raising and lowering the charge from the channels r' , and partly through blast holes r^2 arranged tangentially on a radial section of the surface which is situated directly behind (in reference to the direction of rotation shown by the arrow in Fig. 2) a part of the device which causes the displacement of the charge. By this means none of the fuel or ashes can obstruct said holes, the movement of the latter being always away from and not toward the material in the producer.

What we claim as new and desire to secure by Letters Patent of the United States is:

1. In a gas producer, a revoluble ash bowl and a grate fixed thereupon, said grate having upper surfaces of a substantially interrupted spiral configuration, said surfaces 85 having a very gradual rise terminated by abrupt shoulders of considerable depth and being widely separated angularly, thereby providing only a few upwardly directed 90 projections.

2. In a gas producer a stationary shell and a revoluble ash bowl and a grate fixed thereupon, said grate having the shape of laterally displaced vertical sections of a cylinder and having upper surfaces of a substantially interrupted spiral configuration, 95 said surfaces having a very gradual rise, terminated by abrupt shoulders of considerable depth and being widely separated angularly, thereby providing only a few upwardly directed 100 projections.

3. In a gas producer a stationary shell, a revoluble ash bowl, a grate fixed thereupon and surfaces on the upper side of said grate of spiral configuration symmetrically 105 arranged around a center and having a very gradual rise terminated by abrupt shoulders of considerable depth and being widely separated angularly thereby providing only 110 a few upwardly directed projections.

4. In a gas producer a stationary shell, a revoluble ash bowl, a grate fixed thereupon and surfaces on the whole of the upper side of said grate of spiral configuration, symmetrically arranged around the 115 axis of rotation of the grate and having a very gradual rise terminated by abrupt shoulders of considerable depth and being widely separated angularly thereby providing only a few upwardly directed 120 projections.

5. In a gas producer a stationary shell, a revoluble ash bowl, a grate fixed thereupon, said grate consisting of vertical semi-cylinders eccentrically arranged relatively 125 to each other and to the axis of rotation of the grate in such a way that their cylindrical surfaces at the ends remote from the axis of rotation protrude laterally toward said shell.
